UNITED STATES PATENT OFFICE.

GEORGE L. BAXTER, OF SALT LAKE CITY, UTAH.

WRENCH.

1,157,834.

Specification of Letters Patent.

Patented Oct. 26, 1915.

Application filed February 9, 1915. Serial No. 7,080.

To all whom it may concern:

Be it known that I, GEORGE L. BAXTER, a citizen of the United States of America, residing at 1338 Bryan avenue, Salt Lake city, in the county of Salt Lake and State of Utah, have invented certain new and useful Improvements in Wrenches, of which the following is a specification, reference being had therein to the accompanying drawing.

This invention relates to an adjustable wrench and has for its object the production of a simple and efficient means for facilitating the quick adjustment of the sliding jaw and also conveniently holding the jaw in an adjusted position after the same has once been set.

Another object of this invention is the production of a simple and efficient means whereby the ratchet teeth formed upon the adjustable jaw will be protected by means of the casing adapted to surround the same.

A still further object of this invention is the production of a simple and efficient means for causing the adjustable jaw to be automatically locked as soon as the same has been released.

With these and other objects in view this invention consists of certain novel combinations, constructions, and arrangements of parts as will be hereinafter fully described and claimed.

In the accompanying drawing:—Figure 1 is a side elevation of the wrench. Fig. 2 is a side elevation of the wrench, the locking casing being shown in section, and certain other portions of the wrench being shown in section. Fig. 3 is an enlarged sectional view taken through the lower end of the adjustable jaw and a portion of the handle, showing clearly the action of the spring for throwing the adjustable jaw in engagement with the locking casing. Fig. 4 is a plan view of the blank from which the locking casing is formed.

By referring to the drawing it will be seen that 1 designates the handle which may be provided with teeth formed upon the upper face thereof as indicated by the numeral 2 which may be made straight as indicated by the numeral 3 in Fig. 2 to suit the convenience of the operator. As it is, of course, obvious such changes in construction may be employed without departing from the spirit of the invention.

A locking housing 4 is pivotally secured

to the handle, which casing is formed from a blank sheet of material as clearly illustrated in Fig. 4 of the drawing. This locking housing 4 comprises a pair of side wings 5 which are adapted to be folded to a position to extend parallel to each other and be pivotally secured at their outer ends to the stationary jaw by means of a transversely extending pivot pin 6.

The body portion 7 of the casing 4 is provided with an upwardly projecting tongue 8 which is bent or folded inwardly to produce a wedge-shaped gripping tongue 9 as clearly illustrated in Fig. 2. It should be understood that this tongue 9 is formed by bending the tongue 8 upon the fold line 10, and then bending the outer lip 11 so as to extend at right angles to the main body 7 of the locking casing 4. The lower end of the body 7 is bent outwardly to produce a finger engaging lip 12 to facilitate the throwing of the tongue 9 out of engagement with the teeth 13 formed upon the rear face of the adjustable jaw 14.

A pivot link 15 is connected to the adjustable jaw 14 and is slidably mounted upon the handle 1 as illustrated in Fig. 2 of the drawing. The adjustable jaw 14 is provided near the lower end thereof with a socket 16 within which is mounted one end of a coil spring 17 as clearly illustrated in Fig. 3. This coil spring 17 has its outer end bent inwardly between the convolutions of the coil spring as indicated by the numeral 18, thereby producing a smooth portion for traveling upon the rear face 19 of the handle 1 as illustrated in Figs. 2 and 3.

It should be understood that the adjustable jaw may be operated by pushing inwardly upon the lip 12, thereby causing the spring 17 to be compressed and the tongue 9 to be drawn out of engagement with the teeth 13. This is possible owing to the fact that the adjustable jaw 14 will pivot at the point indicated by the numeral 20, whereas the locking casing 4 will pivot upon the pivot pin 6, thereby allowing the tongue 9 to be drawn out of engagement with the teeth 13 to permit the proper adjustment of the jaw 14.

From the foregoing description it will be seen that a very simple and efficient wrench has been produced of the adjustable type, wherein the teeth upon the rear face of the adjustable jaw may be held out of engagement with foreign objects for preventing

the same from becoming injured or unnecessarily worn. It should be further understood that by means of the present device an adjustable jaw may be readily and conveniently adjusted.

Having thus described the invention what is claimed as new, is:—

An adjustable wrench of the class described comprising a stationary jaw, an adjustable jaw slidably mounted thereon, a locking housing carried by said stationary jaw and passing around said adjustable jaw and adapted to hold said adjustable jaw in a set position, said adjustable jaw provided with a retaining link pivotally secured thereto and passing around said stationary

jaw, said adjustable jaw provided with a socket near one end thereof, a coil spring fitting in said socket and engaging the rear face of said stationary jaw, the free end of 20 said coil spring being bent inwardly to fit between the convolutions of said coil spring for facilitating the sliding of said coil spring longitudinally upon the rear face of said stationary jaw.

25

In testimony whereof I hereunto affix my signature in presence of two witnesses.

GEORGE L. BAXTER.
